UNITED STATES PATENT OFFICE.

FRANKLIN ADELBERT THOMPSON, OF FONDA, IOWA.

HAME ATTACHMENT.

SPECIFICATION forming part of Letters Patent No. 352,432, dated November 9, 1886.

Application filed March 25, 1886. Serial No. 196,541. (No model.)

To all whom it may concern:

Be it known that I, FRANKLIN ADELBERT THOMPSON, a citizen of the United States, residing at Fonda, in the county of Pocahontas and State of Iowa, have invented new and useful Improvements in Hame-Couplings, of which the following is a specification, reference being had to the accompanying drawings.

My invention relates to improvements in hame-couplings; and it consists of the peculiar and novel construction and combination of parts, substantially as hereinafter fully set forth, and particularly pointed out in the claims.

15 The object of my invention is to provide an improved coupling intermediate of the hame-tug or trace and the hame, which shall accommodate itself to the various movements of the parts and reduce the strain and wear on 20 the parts thereof, whereby they will be rendered more durable and less liable to wear out.

A further object of my invention is to provide an improved coupling of the class named, which shall be very simple and strong in its 25 construction, cheap and inexpensive of manufacture, and easily and readily applied or adjusted for use upon the hame and trace.

In the accompanying drawings, Figure 1 is a perspective view showing my improved coupling applied to a hame and trace. Fig. 2 is a 30 detached perspective view of the shank, and Fig. 3 is a similar view of the clamping-plates. Fig. 4 is a central longitudinal sectional view through the coupling-plates and shank connected together.

35 Referring to the drawings, in which like letters of reference denote corresponding parts in all the figures, A designates the hame; B, the trace or tug, which are of the ordinary or any preferred form; and C, my improved coupling intermediate of the hame and tug. The coupling C is provided with a shank, D, that is provided at one end with an integral ball or sphere, d, that is enlarged to a suitable size, 45 and at its opposite end with integral prongs d', that are arranged parallel with and a short distance apart from each other and at a suitable angle to the shank. These prongs are inserted or driven into the hame at a suitable 50 point thereon, so that the shank and sphere or ball project rearwardly and in the plane of

the trace or tug B. The coupling C is further provided with two plates, E, which are preferably rectangular in form, and provided with apertures e, through which are passed the rivets that secure the plates to the hame-tug or trace, said plates lying on opposite sides of the trace or tug, at the extreme forward end thereof. The front ends of these plates are provided with integral hollow enlargements 55 or heads F, that form a socket for the reception and retention of the ball or sphere of the shank D, whereby a ball-and-socket joint is provided between the hame and trace, which permits of a free movement of the parts, and 60 enables the hame and trace to adapt themselves to the motions of each other, and reduces the strain and wear to render them more durable. The front edges of the hollow semi-circular portions or heads F are recessed, as 65 at f, and the edges thereof beveled to provide for the passage of the shank D, and permit the free rotation thereof; and intermediate of the hollow socket or head and the plates is provided a reduced neck, G, which is curved 70 transversely and provided with an aperture, g, for the passage of a rivet or bolt, g', to secure the plates together.

To apply or adjust my improved coupling, the prongs of the shank are inserted or driven 80 into the hame, and the ball or sphere d fitted in the socket or head F of the plates E, which are then fitted on opposite sides of the hame-tug or trace, and secured thereto and to each other by means of the rivets. The curved neck 85 and head of each of the plates are provided with projecting portions h, that lie out of the plane of the inner faces of the plates, and when these plates are adjusted upon the trace or tug, these projecting portions of the head and neck come and fit together very squarely and firmly, and the space of proper width is provided between the plates for the insertion or reception of the trace or tug.

The device is very easily and readily adjusted and secured in place, and it is very durable and simple in construction and cheap and inexpensive of manufacture, the entire coupling being cast in three pieces.

I am aware that it is not new to provide a 90 ball-and-socket coupling intermediate of the hame and the trace, and hence I do not claim

this feature, broadly, but confine myself to the peculiar features of construction herein shown and described.

Having thus described my invention, what I claim as new, and desire to secure by Letters Patent, is—

1. A hame-coupling comprising a shank having an enlarged ball or head and the angular prongs adapted to be attached to the hame, and the coupling-plates provided with the hollow socket for the reception of the ball or head, substantially as described.

2. As an improved article of manufacture, a hame-coupling cast in three pieces and comprising a shank having a head or ball, and the prongs adapted to be attached to the hame and the plates, each having a hollow recessed head and a reduced neck intermediate of the plate and head, substantially as described.

3. As an improved article of manufacture, 20 a hame-coupling comprising a shank having an integral enlarged ball or head, and the angular integral prongs arranged parallel with each other, and the two coupling-plates, each having the enlarged and hollow heads and reduced necks, all cast in one piece, the plates and necks having the rivet-apertures, and the hollow heads the recessed front ends, *f*, substantially as described.

25 In testimony that I claim the foregoing as 30 my own I have hereto affixed my signature in presence of two witnesses.

FRANKLIN ADELBERT THOMPSON.
